METHOD OF MOLDING HOLLOW CONCRETE BLOCKS

Michael vande Cuypers, New York, N. Y.

Application February 12, 1947, Serial No. 728,165

8 Claims. (Cl. 25—155)

1

This invitation relates to a method of manufacturing concrete blocks and similar concrete articles, and has for its object the provision of a continuous method by which the blocks may be speedily and economically made.

The invention also contemplates for one of its objects, the provision of a novel type of concrete block provided with diagonally extending or angular reinforcing webs, resulting in a block of lightness, strength and durability and with the useage of a minimum of material.

Still another object of the invention is to provide a method of making blocks of this character, wherein the concrete for the formation of the blocks is sprayed under pressure on a moving conveyor and about suitable forming elements, whereby the method thus employed for the formation of the blocks is continuous and uninterrupted and the blocks can be produced speedily and very economically.

More particularly, the invention contemplates the provision of a travelling conveyor or belt constituting a moving form adjacent to which a plurality of spaced cement guns or sprayers are operated to thereby direct the concrete in more or less fluid form upon the belt and around spacing elements or form parts placed upon the belt in proper sequence and as required to produce the blocks of requisite form and shape, so that at the end of travel of the belt or conveyor, the blocks can be removed and set aside for curing.

In the accompanying drawing, wherein an illustrative embodiment of the invention is disclosed, Fig. 1 is a longitudinal sectional view through a conveyor constructed in accordance with the invention, and showing the manner in which concrete blocks are formed thereon; Fig. 2 is a sectional view on the line 2—2 of Fig. 1, looking in the direction of the arrows, and Fig. 3 is a perspective view of a concrete block constructed in accordance with the invention.

Referring to the drawing, 1 indicates a continuously-moving travelling belt or similar conveying means proceeding in the direction of the arrows and upon which the concrete blocks, and example of which is shown at 2 in Fig. 2, are made. The belt of conveyor 1 may be moved by any known means and the same is shown as being supported by a plurality of idle rollers 3.

Extending along the sides of the belt or other conveyor 1 are the side form members 3a and 4 which are vertically disposed walls or boards and which serve to cooperate with the belt in the formation of a trough-shaped form, and which further constitute retaining walls which serve to

2

confine the concrete deposited on the belt, between them. These retaining walls 3a and 4 may be stationary or may be arranged for movement along with the conveyor belt 1.

5 The first step in carrying out the improved method of manufacturing concrete blocks of the character shown in Fig. 2, consists in depositing an initial layer 5 of concrete on the travelling belt 1 by means of one or more concrete guns or nozzles indicated at 6. These guns or nozzles may, if more than one is required at this station, be arranged in a line extending transversely of the belt 1 or in a group located above the belt so that the fluid, or nearly fluid, concrete sprayed 15 therefrom, as indicated at 7, will be directed downwardly from the nozzles and be deposited on the belt and between the walls 3a and 4 in a substantially uniform layer 5, subsequently forming one of the walls or faces of the concrete block, as clearly seen in Fig. 2.

The belt 1 carrying the deposited concrete layer 5, proceeds to the next station, indicated at 8, where one or more concrete guns or nozzles directs a second layer of concrete 9 upon the conveyor. It will be observed however, that between the concrete-depositing stations 6 and 8, form pieces 11 are placed transversely across the belt and on top of the concrete layer 5. These form pieces 11 may be deposited either manually or by suitable mechanism and are substantially triangular in cross-sectional shape in order to form the passages 12 of similar shape through the block. It will thus be observed that when the layer 9 is deposited by the guns or nozzles at station 8, the layer will thus be deposited on top of the form pieces 11. The form pieces 11 and 13, as well as the face of the belt 1 are suitably oil-coated or otherwise treated to prevent adherence of the concrete to them.

40 Directly after the deposit of the concrete layer 9, a second series of form pieces, indicated at 13 is placed on top of the layer 9 and at positions intermediate of the form pieces 11. The form pieces indicated at 13 are shown as being substantially square in cross-sectional shape and they thus result in the formation of the central passages 14 through the block.

45 The conveyor then carries the deposited materials, including the form pieces 11 and 13 to the next filling station, indicated at 16, where one or more concrete guns or spray nozzles, deposit a layer of concrete indicated at 17, on top of the form pieces 13. After this is done, the final group of triangulated form pieces 19 is laid in place. This last set of form pieces 19 produces

the passages indicated at 18 through the block. After the last-mentioned form pieces 19 are placed in position, a final layer of concrete, indicated at 20 is deposited by one or more concrete guns or spray nozzles at station 21, upon top of the form pieces 19, this last layer of concrete being that which constitutes the second wall or facing 22 of the block 2.

To separate the several layers of concrete so deposited on the belt into blocks of required length, separators are provided, the same being shown at 23 in Fig. 1. In the form shown, these separators consist of blades or fins projecting from certain of the form pieces 13 and tending to interrupt the continuity of the facing layers 20 and 5 as well as interrupting the continuity of the layers 9 and 17. Thus, by the placement of the form pieces 13 provided with the separators 23, at the desired points in the deposited concrete, the formed blocks 2 of required length will be produced.

A block formed by the method above described is shown in Fig. 2 wherein it will be noted that the same is provided with the two parallel facing webs or walls 5 and 22, connected by the diagonally extending truss webs 24. This block because of its internal truss-work, is of exceptional strength. It will be noted that at its opposite ends, the block is V-shaped or is formed with the notches 26 in which the mortar can engage thus aiding greatly in bonding blocks of this character together in any wall or building structure.

In describing the method by which the blocks are made, I have herein described a block of certain configuration, namely, that shown in Fig. 2. It will be understood that the method of manufacture is not limited to that particular block, as the formation of many different types of block by the method disclosed is primarily dependent upon the placement and shape of the inserts or form pieces. Thus, the block herein described is merely illustrative of one form of block which can be made and it will be obvious that other forms are possible and are considered as within the scope of the invention.

The concrete guns or spray nozzles employed at the stations 6, 8, 16 and 21 may be those conventionally employed for the spraying of concrete in substantially liquid form, or they may be of other construction and by means of which the liquid concrete mix is forcibly ejected under pressure and as a result is firmly compacted upon the surface against which it is sprayed. The result of such deposit of the concrete is to secure blocks of very satisfactory density and of extraordinary strength and great durability.

Having described my invention, what I claim is:

1. The method of making hollow concrete blocks consisting in depositing successive layers of concrete in substantially fluid form upon a traveling conveyor, and in depositing form pieces on the conveyor between the deposit of the several concrete layers and removing the form pieces to thereby provide passages extending through the resultant concrete blocks.

2. In the method of making hollow concrete blocks, the step of spraying a layer of concrete on the surface of a travelling conveyor, in placing inserts on top of said layer, and in spraying a

second layer of concrete on top of the inserts and thereafter removing the inserts.

3. In a method of making hollow concrete blocks as provided for in claim 2, including providing separating elements on the inserts to thereby interrupt the continuity of the layers of concrete deposited on the conveyor.

4. In the method of making hollow concrete blocks, the step of spraying a layer of concrete on a travelling conveyor, placing a plurality of form pieces across the conveyor on top of the layer of concrete, spraying a second layer of concrete on top of the form pieces, placing a second set of form pieces on top of the second layer of concrete and intermediate of the first set of form pieces, spraying a third layer of concrete on top of the second set of form pieces, placing a third set of form pieces on top of the third layer of concrete, and spraying a final layer of concrete on top of the third set of form pieces.

5. In the method of making hollow concrete blocks, the step of spraying a relatively flat and even layer of concrete upon the flat surface of a travelling conveyor, placing a plurality of form

pieces in spaced relation across the conveyor and on top of the layer of concrete, spraying a second layer of concrete on top of the form pieces to follow the shape of said form pieces, depositing a second set of form pieces on top of the second layer of

concrete and placing the last-mentioned form pieces intermediate of the first set, depositing a third layer of concrete on the conveyor on top of the last-mentioned set of form pieces, placing a final set of form pieces with their outer surfaces

parallel to the upper face of the conveyor on top of the third layer of concrete, and depositing a final layer of concrete on top of the last-mentioned set of form pieces, the final layer of concrete being deposited to form a layer substantially parallel to the first layer deposited on the conveyor.

6. In a method as provided for in claim 5, wherein the first and last layers of concrete are deposited so that the same lie substantially parallel, and the second and third layers of concrete are angularly disposed to thereby form diagonally-extending webs in the resultant concrete block.

7. In the method of making a hollow concrete block, the steps of spraying successive layers of concrete at spaced-apart spraying stations on a travelling conveyor and depositing transversely extending form pieces on the conveyor between the stations at which the successive layers are sprayed.

8. In the method of making hollow concrete blocks, the steps of spraying successive layers of concrete on a travelling conveyor, depositing form pieces across the conveyor and between the layers, and in providing separating means by which outer layers of the concrete so sprayed are interrupted.
